UNITED STATES PATENT OFFICE.

GEORGE H. BRINTON, OF PHILADELPHIA, PENNSYLVANIA.

SYRINGE.

SPECIFICATION forming part of Letters Patent No. 351,736, dated November 2, 1886.

Application filed May 7, 1886. Serial No. 201,489. (No model.)

To all whom it may concern:

Be it known that I, GEORGE H. BRINTON, a citizen of the United States, residing at the city of Philadelphia, in the State of Pennsylvania, have invented a new and useful Syringe, of which the following is a specification.

This invention relates to a syringe in which the piston-head may be connected with and disconnected from the piston-rod at the will of the operator; and the object of my invention is to so construct the syringe that it may be used for the purpose of carrying the liquid within the syringe, and thereby dispense with the bottle or other receptacle ordinarily used for that purpose, which object I accomplish by means of the mechanism illustrated in the accompanying drawing, in which—

The figure shows a longitudinal sectional view of a syringe constructed in accordance with my invention.

In the drawing, A represents the shell or case, which may be made of any suitable material, and is constructed in the ordinary manner.

25 D is the piston rod or stem.

F is the piston-head, which head is provided with the packing G. It is also provided with the screw-thread E.

B is a screw-thread upon the piston-rod, 30 made of suitable size to engage with the screw-thread E.

C is the end of the piston-rod, which may be constructed so as to form a cork or stopper for the small end of the syringe.

35 In filling the syringe with liquid the piston-rod D is drawn back until the screw B is brought in contact with the screw-thread E, when the piston-rod is turned to the right, engaging the screw-thread B with the screw-threads E, 40 thereby attaching the piston-head to the piston stem or rod. The piston-head is then carried to the end of the syringe-tube near the tip. The tip being placed in the liquid, the piston-head is drawn back to the other end of 45 the cylinder or tube with the liquid. By turning the piston-rod to the left the screw-thread

B disengages from the screw E in the piston-head. The piston-rod is again pushed forward toward the point or tip of the syringe until the part C entirely closes the opening. 50 This leaves the syringe filled with liquid between the piston-head F, which is at the butt or upper end of the syringe, and the cork or stopper C, which is at the lower or point end of the syringe. The piston-head being packed 55 both at its periphery, where it comes in contact with the case, and around the piston-rod at G, retains or prevents the liquid from escaping at one end of the syringe, and the stopper C prevents it from escaping at the other 60 end of the syringe. In this way the liquid can be carried in the syringe for any length of time desired, and whenever the operator desires to use the syringe he has only to draw back the piston-rod, turn it, thereby engaging the screw-threads B with the screw-threads 65 E, connecting the piston-rod to the piston-head, when the syringe is used in the ordinary manner.

While I deem it advisable to provide the 70 piston-rod with the stopper C, yet it may be dispensed with in some cases, if desired, as the liquid would not escape to any extent in case the point of the syringe was kept uppermost.

Having thus described my invention, what 75 I claim to have invented, and desire to secure by Letters Patent, is—

In a syringe, the combination of the piston-rod D, a detachable head, F, provided with a screw-thread, E, and the cork or stopper C, 80 provided with the screw-thread B, to engage the screw-thread E, said stopper C adapted to prevent the liquid from escaping at the tip end of the syringe, and said piston-head F adapted to prevent the liquid from escaping 85 at the other end of the syringe, substantially as described.

GEO. H. BRINTON.
